UNITED STATES PATENT OFFICE.

GEDOR W. ALDEEN, OF ROCKFORD, ILLINOIS, ASSIGNOR TO NATIONAL LOCK CO., OF ROCKFORD, ILLINOIS, A CORPORATION OF DELAWARE.

LOCK.

Application filed May 9, 1927. Serial No. 189,817.

This invention relates to a lock of the type whose case is mortised into the edge of a drawer and whose key cylinder is removably insertable into the case through a 5 hole cut in the drawer and intersecting the mortise.

One of the objects of this invention is to provide a lock having a removable key cylinder, the cylinder also having a knob 10 by means of which the bolt may be actuated, the cylinder therefore being held rotatably in the case.

Another object of this invention is to provide a rotatable key cylinder which carries 15 a rotatable key guide, the cylinder being insertable into a lock case and automatically locked in operative position.

Another object of this invention is to provide a key cylinder rotatably carrying a 20 key guide, insertable into a lock case, and automatically locked in the case when inserted, together with means for unlocking the cylinder to permit its withdrawal from the case.

Another object of this invention is to provide a lock whose case may be mortised into a drawer wall and whose key cylinder 25 is insertable into the case through a hole perpendicular to the mortise, the key cylinder having a knob for actuating the bolt, and adapted when inserted into the case to engage bolt actuating means, and at the same time being releasably locked in a rotatable position in the case.

Other inherent objects, advantages and 30 capabilities of this invention will later become apparent.

Referring to the drawings, in which a preferred embodiment of the invention is 35 shown for the purpose of illustrating the invention,

Fig. 1 is a front elevation of the lock case with the cover removed and with the cylinder in section and showing the mechanism 40 of the lock in its unlocked position,

Fig. 2 is a vertical, central section showing the knob and case as they are mounted 45 in the wall of a drawer,

Fig. 3 is a vertical central section on the line 3—3 of Fig. 2,

Fig. 4 is a horizontal section taken on the line 4—4 of Fig. 3,

Fig. 5 is an elevation of the knob and key cylinder as detached from the case, whereas

Fig. 6 is an end elevation of the knob 55 and cylinder shown in Fig. 5, and

Fig. 7 is an elevation of the bolt actuator alone.

Referring now to the drawing, a lock case generally indicated as 11 is inserted into a mortise as shown in Fig. 2 in the wall 12 of such as a desk drawer. When inserted to its full depth, the face plate 13 is then secured to the top surface of the drawer by means of screws extending through 65 the openings 14 in the face plate.

The bolt 15 extends through the face plate and is adapted to be reciprocated by the knob 16.

The bolt is provided with an extension 70 17 which slides within the case against the back wall and is provided with a notch 18 into which extends the projection 19 on the bolt actuator 21. The actuator oscillates about a horizontal axis. An extension 22 75 on the actuator rotatably fits into a hole 23; the rear face 24 of the actuator then bears against the rear wall of the case and slides over it as the actuator is oscillated about its horizontal axis. It will be understood that so long as the projection 19 is 80 engaged in the notch 18 in the bolt, any oscillation of the actuator will cause the bolt to be withdrawn into or extended from the case. The preferred embodiment of this 85 invention discloses a lock in which the bolt is normally urged to remain in extended position by means of a spring 25 pivoted on post 26 and bearing against a surface of a slot 20 in the head of the bolt.

The bolt is reciprocated by the oscillation of the bolt actuator while the actuator itself is oscillated by the rotation of the key cylinder. This latter result is accomplished by means of the dogs 27 on the inner extremity of the barrel 28 which extend 90 into and engage with the slots 29 in the actuator. The enlarged portion 16 of the key cylinder is formed integrally with the barrel portion 28 and is the only part which 95 extends out beyond the outer surface of the wall of the drawer, as shown in Fig. 4. This portion 16 constitutes a knob which 100 may be conveniently grasped for rotating the key cylinder and bolt actuator to unlock 105 the drawer and for pulling the drawer out after it is unlocked.

The barrel or key cylinder 28 finds a

bearing during its rotation on the front cover 31 of the case along the edges of the hole 32 through which the barrel portion of the key cylinder extends. The inner end of the barrel is supported by the actuator 5 into which the dogs 27 extend; hence as the actuator has an axial bearing on the case, the key cylinder is thereby given a second point of support for its rotational movement in addition to its direct bearing 10 on the front cover of the case. In consequence, the key cylinder and key guide 33 will always be held perfectly horizontal. If the key is allowed to remain in the key cylinder while the lock is unlocked, it too 15 will be held perfectly horizontal, will not interfere with the rotation of the cylinder, and will present a neat appearance.

The key guide 33 is carried centrally by 20 the key cylinder and is held therein rotative relatively to the cylinder by means of a disk 34 integral with the key guide and seated in the annular recess 35 in the outer end of the knob. The inner end of the key 25 guide has a reduced portion 36 which fits into a central opening 37 in the actuator and a longitudinal slot 38 is provided in the key guide and extends from the center line of the key guide outwardly to its surface, 30 thus acting as a suitable guide for the key which may be inserted through the cylinder for purposes hereinafter described.

The means of locking the bolt in extended position is provided for as follows. A bolt 35 locking slide 39 lies next to the bolt extension 17 and reciprocates up and down in the case on the face of said bolt extension. A lug 41 formed integrally with the rear wall of the case guides the reciprocatory motion 40 of the bolt extension and the bolt locking slide. Another lug 42 which is likewise mounted on the rear wall of the case guides the upper portion of the bolt locking slide in its reciprocatory motion. The bolt locking slide is provided with a notch 43 into 45 which a projection on the key may extend for the purpose of reciprocating the bolt locking slide from locked to unlocked position and back again. This notch and the 50 key which cooperate with it are so designed that a projection on the key may rotate into the notch, cause the slide to move up or down provided the slide itself is not locked, and at the limit of travel of the 55 slide the key projection will thereafter rotate completely out of the notch leaving the slide at its uppermost position as shown in Fig. 3 or in its lowermost position, that is, when the bolt is unlocked for free movement as illustrated in Fig. 1. As shown in Fig. 3, the upper left hand corner 44 of the bolt locking slide abuts against the lower right hand corner of the bolt and thus holds the bolt from being withdrawn 60 into the case. Hence when the locking slide 65

is in its lowermost position, the bolt may be freely reciprocated. It should be understood that the bolt itself is urged to extended position by means of the spring but may be reciprocated back and forth by the oscillation of the actuator, the actuator being oscillated by the knob. The locking slide itself is moved to its locked or to its bolt locking position or bolt unlocking position by means of a projection on a key. 70 75

The locking slide itself is locked in its uppermost position by a cooperation existing between a lug 45 formed on the locking slide and extending toward the front of the case, the inner tumbler 46 and a middle tumbler 47 which are pivoted on the same post 48, each being urged toward the center of the case by means of springs 49 and 51 which bear against the inner wall of the case. These two tumblers are suitably slotted as 80 illustrated to permit the lug 45 to reciprocate longitudinally in their slots whenever the tumblers are pressed sufficiently away from the center of the case by means of key projections which cooperate with each of them. As illustrated in Figs. 1 and 3, these tumblers cooperate with the lug 45 to hold the locking slide either in unlocked or locked position. As the key is rotated into the notch 43 of the lock slide, it simultaneously 95 actuates the two tumblers to disengage them from the lug 45 in order that the key may then move the lock slide away from the position in which the tumblers have been holding it locked. 100

The manner of actuating the bolt, locking the bolt in extended position and all of the necessary mechanism for doing these several things has been described above. There now remains to be described the means for locking the key cylinder against separation from the case yet permitting it to be rotated for the purpose of reciprocating the bolt. A cylinder locking tumbler 52 is pivoted on the post 48 also and has a spring 53 which urges it toward the center of the case. The travel of this outermost tumbler 52 toward the center of the case is limited by the abutment of its extension 54 on the lug 45. No matter whether the lock slide and its lug 45 are in upper or the lower position, this engagement 115 will occur and will prevent the tumbler from moving too far toward the center of the case. A dog 55 extends toward the center of the case and loosely engages with an arcuate 120 notch 56 in the barrel of the key cylinder. This dog and the cylinder are so designed that whenever the cylinder is thrust into the case, the end of the dog will ride along the cam surface 57 on the barrel 28 causing the third tumbler 52 carrying this dog to be pressed back somewhat until the cylinder is pushed all the way into the case with the lugs 27 engaging with the actuator, whereupon 125 this dog 55 will then spring into the notch 130

56 and thereafter prevent withdrawal of the key cylinder from the case until by some means the dog is later disengaged from this notch.

- 5 Provision for the release of this dog from the notch in the key cylinder is made by the designing of a key 58 which may be inserted in the usual manner through the key guide and which when rotated will strike the end 10 of the dog 55 and push it back away from the center of the case past the corner 59 thereby permitting the cylinder to be withdrawn from the case. The key 58 is adapted to push the dog out of engagement with the 15 key cylinder notch but the ordinary key used for the actuation of the tumblers and lock slide is provided with a recess so that during its rotation it will always miss this dog. The arcuate slot 56 in the barrel 28 is long enough 20 to permit a free rotation of the knob without the end of the dog 55 touching the closed end of this notch. The bolt in the lock illustrated is moved between the limits of its reciprocatory travel by less than 90° of rotation 25 of the knob, hence the notch 56 need not be very long.

Looking at Fig. 3 where the locking mechanism is in bolt locking position, clockwise rotation of the key will unlock the tumblers 30 and move the bolt locking slide 39 to its lower position. Likewise a short clockwise motion of the knob after the bolt is unlocked will cause the bolt to be retracted within the case. Counter-clockwise rotation of the locking key will push the tumblers 46 and 47 aside to allow the key to move the bolt locking slide from the position shown in Fig. 1 to the position shown in Fig. 3. In this latter position the knob cannot be rotated and 40 the bolt is locked in extended position. The cylinder releasing key 58 will unlock the knob locking tumbler 52 and permit the removal of the knob whether or not the bolt at the time is locked or unlocked.

45 It should be understood that the scope of this invention is not limited to the structure illustrated and described herewith as it also comprehends various modifications which may differ in construction but not in spirit 50 from the preferred embodiment herewith illustrated.

Having shown and described the invention, I claim:

1. In a lock, a case, a bolt, a key cylinder 55 extending into said case, means operatively connected with the key cylinder for actuating the bolt and means disconnectably engageable with said cylinder for locking the cylinder in operative position.
2. In a lock, a case, a bolt, a rotatable key cylinder adapted to extend into said case, means operatively connected with the key cylinder for actuating the bolt and means for engaging said cylinder as the cylinder 60 is pushed into the case to disconnectably

lock the cylinder thereafter in operative position.

3. In a lock, a case, a reciprocable bolt, a key cylinder extending into said case for actuating said bolt, means operatively connected with the key cylinder for actuating the bolt and means extending into said cylinder for normally engaging said cylinder to hold the cylinder in operative position.

4. In a lock, a case, a bolt, a bolt actuating means, a key cylinder extending into the case and adapted to engage and move said means to actuate the bolt, and means for lockingly engaging said cylinder when it is thrust into the case to hold it in operative position.

5. In a lock, a bolt, bolt actuating means including a knob, and key-released means for locking said knob in operative connection with the bolt.

6. In a lock, the combination of a lock case, a key cylinder rotatably and detachably connected with said case, a key guide rotatably mounted in said cylinder and means for releasably locking the cylinder in rotatable position.

7. In a lock, a reciprocable bolt, a bolt locking slide, a bolt actuator, means for locking said slide in two positions, a key cylinder operatively engaged with said actuator, and a tumbler normally engaged with said cylinder to hold the cylinder and actuator in engagement.

8. In a lock, the combination of a lock case, a bolt, a rotatable bolt actuator having an axial bearing on said case, and a key cylinder detachably connectible with said actuator.

9. In a lock, the combination of a lock case, a bolt, a bolt actuator supported on said case, and a key cylinder detachably connectible with the actuator for operating the actuator.

10. In a lock, the combination of a lock case, a bolt, a movable key cylinder having a portion extending into said case, means operatively connected to the cylinder for actuating the bolt, and means for releasably locking said cylinder portion in said case.

11. In a lock, the combination of a lock case, a bolt, a movable key cylinder having a portion extending into said case, means operated by movement of the cylinder for actuating the bolt, and means for releasably locking said cylinder portion against separation from the case but in movable relation to said case.

12. In a lock, the combination of a lock case, a bolt, a rotatable key cylinder having a portion extending into said case, means operated by movement of the cylinder for actuating the bolt, and means for releasably locking said portion against separation from the case but in rotatable relation to said case.

13. In a lock, a case, a bolt, a rotatable

key cylinder, means operatively connected with the key cylinder for actuating the bolt, and means for releasably locking the key cylinder in operative position in the case.

5. 14. In a lock, a case, a bolt, a rotatable key cylinder, means operatively connected with the key cylinder for actuating the bolt, and means for releasably locking the key

cylinder in operative position in the case, said cylinder locking means being adapted to be unlocked when the bolt is in locked and in unlocked position.

In witness of the foregoing I affix my signature.

GEDOR W. ALDEEN.
